LUMINOUS PROJECTILE.

1,090,007.

Specification of Letters Patent. Patented Mar. 10, 1914.

Application filed October 1, 1913. Serial No. 792,813.

To all whom it may concern:

Be it known that I, FRIEDRICH ZIEGENFUSS, residing at Essen-on-the-Ruhr, Germany, a subject of the Emperor of Germany, have invented a certain new and useful Improvement in Luminous Projectiles, of which the following is a specification.

This invention relates to luminous projectiles and particularly to those luminous projectiles whose illuminating bodies are provided with parachutes and are ignited during the flight of the projectile and simultaneously released by a charge of the projectile.

In the accompanying drawing, one embodiment of the invention is illustrated by way of example.

In said drawing Figure 1 is an axial longitudinal section of the luminous projectile. Fig. 2 is a section on the line 2-2 of Fig. 1, and Fig. 3 is a section on the line 3-3 of Fig. 1.

The projectile body A receives two illuminating bodies each of which possesses a kettle shaped container B for the illuminating mass C and a parachute D. The illuminating mass is fixed in the container B through means of a cover plate F carried by a bolt E. In the cover plate perforations f¹ are provided, which terminate over a ring c¹ of pressed powder, designed for their ignition. The bolts E are threaded into the bases of the appropriate containers and are constructed beyond the containers, with a swivel e¹ for a shackle e² to which the parachute D is secured.

The two luminous bodies are so arranged in the body of the projectile that their illuminating masses are presented toward a bursting charge G located in the middle of the projectile body (see also Fig. 2). This bursting charge consists of a series of small bodies, which are pressed into a ring G¹ and stand in communication with one another through means of a groove g² arranged in the outer periphery of the ring. Moreover each bursting body is connected through a radial channel g³ with the inner chamber of the ring G¹. For igniting the bursting charge, powder bodies H are employed, which are located in a groove a¹ extending approximately over the entire length of the projectile body, and standing in communication, by means of a channel i¹ with the igniting composition i² of a time

fuse J which constitutes the head of the projectile. Between the ring G¹ and each of the two illuminating bodies is introduced a centrally arched disk K. These disks are provided in their arched portions with perforations k¹ which enable the fire of the bursting charge to gain access to the powder rings c¹ and to weaken the effect of the bursting charge upon the illuminating masses to such an extent that the illuminating masses will not be destroyed by the pressure due to the explosion of the bursting charge.

The two illuminating bodies and the bursting charge lying between them are fixed in the projectile body through means of bushings L and M. Of these bushings, one (L) is sustained on the one side against the projectile base N and on the other side against the container B of the lower illuminating body, while the other (M) abuts against the fuse J and the container B of the upper illuminating body. The bushings L, M receive the parachutes D and consist each of two half cylinders so that after the bursting of the projectile body, they will be thrown asunder through the influence of centrifugal force and release the parachutes.

The mode of operation is as follows: The fire of the igniting charge i² of the time fuse J will be conducted through the powder bodies H to the bursting charge G and communicated through the channel g², to all of the bursting bodies. By the explosion of the bursting charge, the projectile body is torn asunder, so that the illuminating bodies will be free. Simultaneously the fire of the bursting charge is communicated through the perforations k¹, f¹ and the powder rings c¹, to the illuminating masses C, so that these commence to burn. The bushings M, L are separated by centrifugal force, and air resistance acts upon the parachutes and unfolds them. The illuminating bodies, while their illuminating masses burn, fall slowly to earth. In consequence of the weakening of the projectile body A through the groove a¹ the tearing apart of the projectile body by the bursting charge is facilitated, so that the illuminating bodies will be set free with certainty at the bursting point of the projectile. Inasmuch as the release of the illuminating bodies is effected by the splintering of the projectile body, the projectile body can be constructed

of cast iron. This material is not available for the projectile bodies of illuminating projectiles which are constructed in the form of base chamber shrapnels since the projectile bodies of such illuminating projectiles must possess great strength in order to insure the expulsion of the illuminating bodies. Thus by the described arrangement admitting of the use of cast iron, the production of luminous projectiles is essentially cheapened. Moreover, the described projectile, compared with luminous projectiles constructed like a base chamber shrapnel, affords the advantage that at least one (the rear) illuminating body falls to earth from the bursting point of the projectile since its energy exerted in the direction of continued flight is wholly or approximately arrested by the explosion of the bursting charge.

20 The location at which the illuminating effect is produced with the present projectile, may thus be determined with substantial exactness.

I claim:

- 25 1. An illuminating projectile comprising an easily exploding projectile body, an intermediately arranged bursting charge in said projectile body and two parachute illuminating bodies arranged in said projectile body with their illuminating masses presented toward the bursting charge.
- 30 2. An illuminating projectile comprising an easily exploding projectile body, an intermediately arranged bursting charge in said projectile body and two parachute illuminating bodies arranged in said projectile body with their illuminating masses presented toward the bursting charge; protecting disks between the bursting charge and each illuminating mass.
- 35 3. An illuminating projectile comprising

an easily exploding projectile body, an intermediately arranged bursting charge in said projectile body and two parachute illuminating bodies arranged in said projectile body with their illuminating masses presented toward said bursting charge; protecting disks between the bursting charge and each illuminating mass, arched toward the bursting charge to adapt them to resist pressure of the latter.

4. An illuminating projectile comprising an easily exploding projectile body, an intermediately arranged bursting charge in said projectile body and two parachute illuminating bodies arranged in said projectile body with their illuminating masses presented toward said bursting charge; protecting disks between the bursting charge and each illuminating mass, arched toward the bursting charge to adapt them to resist pressure of the latter.

5. An illuminating projectile comprising an easily exploding projectile body, an intermediately arranged bursting charge in said projectile body and two parachute illuminating bodies arranged in said projectile body with their illuminating masses presented toward the bursting charge, said projectile body having in its inner cylinder wall, a groove extending longitudinally and approximately the length thereof.

The foregoing specification signed at Barmen, Germany, this 10th day of September, 1913.

FRIEDRICH ZIEGENFUSS. [L. s.]
In presence of—
ALBERT NUFER,
TOS KUCK.
